LIGHTING FIXTURE.

1,416,664.

Specification of Letters Patent. Patented May 16, 1922.

Application filed May 15, 1919. Serial No. 297,265.

To all whom it may concern:

Be it known that we, MARQUETTE A. HEALY and WALTER I. KIRK, citizens of the United States, residing at Chicago, in the county of Cook and State of Illinois, have invented a certain new and useful Improvement in Lighting Fixtures, of which the following is a full, clear, concise, and exact description, reference being had to the accompanying drawings, forming a part of this specification.

Our invention relates to lighting fixtures and especially to a lighting fixture adapted for use upon an upright piano or similar instrument.

One of the objects of the invention is to provide a practical and effective lighting fixture of the class specified.

Another object of the invention is to arrange for the automatic control of the light, so that it may be lighted and put out automatically.

Another object of the invention is to arrange for the adjustment of the fixture so that the light may be placed in an advantageous position with reference to the article to be lighted.

Another object of the invention is to permit the control of the light to be brought about automatically by the adjustment of the fixture, permitting the light to be lighted when the fixture is adjusted in one position and to be put out when the fixture is adjusted in another position.

Another object of the invention is to secure the foregoing and other desirable results in a simple and expeditious manner.

In the accompanying drawings Fig. 1 is a view partly in elevation and partly in vertical section of a portion of a piano or other instrument provided with a lighting fixture embodying our present invention;

Fig. 2 is a horizontal section taken on line 2-2 in Fig. 1.

In the drawings we show an upright member 1 which is understood to be part of a piano or other instrument or article to which the lighting fixture is to be applied.

The lighting fixture is shown provided with a bracket member 2 which is secured to the upright member 1 as by screws 3. A movable or sliding member 4 is arranged within the member 2 and arranged to slide lengthwise of the same in a telescopic manner. At the outer end of the member 4 there

is a vertically arranged tubular member 5 which is firmly secured to said member 4 and carries at its upper end a shade 6 in which is arranged an electric lighting bulb 7. The insulating wires or conductors 8 and 9 are arranged within the tubular member 5 and pass out of the same through the tubular slide 4 and thence to a switch 10 which is mounted in a recess 11 in the member 1. The movement of the slide 4 longitudinally within the tubular extension 2^a of the bracket 2, obviously adjusts the light 7 toward and away from the member 1.

As a matter of further improvement, the switch 10 is arranged and connected so that the movement of the slide 4 with the light 7 causes the switch 10 to automatically light and extinguish said lamp 7, preferably lighting said lamp when it is pulled out and extinguishing it when it is pushed in. To such end the switch 10 consists of a type of switch having a longitudinally movable plunger 12 mounted on the end of a spindle 13, on the other end of which is a double cone-shaped member 14, the member 14 being arranged within a casing made of insulating material and consisting of two parts 10^a and 10^b. Another member 15 also made of insulating material, is fitted within the casing 10^b and carries a pair of metal contacts 16-16, which contact strips 16-16 are mounted on opposite sides of an aperture 17 in said member 15. A sliding contact member 19 is arranged to work within the member 10^a and to move toward and away from the member 15 so that said member 19 may come into contact with the strips 16 and also be separated from the same. To such end the member 19 is in the form of a small metal casing arranged over or around the member 14 and loosely fitted over the same so that it may be moved relatively to said member 14 in a direction lengthwise thereof. Within the casing 19 is a spring 20 made by arranging a small coiled spring around the member 14. This spring 20 tends to slide the member 19 toward either one of the small ends of the member 14, according as said coiled spring is mounted on either one or the other of the ends of said member 14. Thus when the plunger 12 is in a pushed in position as shown in Fig. 1, the spring 20 will slide the member 19 toward the left hand end of said member 14 and thereby separate the contact casing member 19 from the contact strips 16.

When, however, the plunger 12 is in a pulled out or extended position, as shown in Fig. 2, the spring 20 will slide the member 19 toward the right hand end of the member 14 and thus press said member 19 against the contact strips 16. In the first instance the contacts 19 and 16 will be separated and the circuit thereby broken, whereas in the second instance, said contacts will be in contact with 10 one another and the circuit closed.

As an arrangement for permitting the slide 4 to automatically control the connections of the switch 10, a push rod 22 is secured to the plunger 12 and extended into 15 the bracket 2, so that the adjacent end of the slide 4 will strike against the rod 22 and thereby push said plunger 12 inwardly or into retracted position when said slide 4 is pushed inwardly within the bracket 2. 20 Also a chain connection 23 is made between the slide 4 and plunger 12 so that when the slide 4 is pulled outwardly the plunger 12 will also be pulled outwardly and thereby moved to its outwardly or extended position. Thus the inward movement of the slide 4 and consequently the inward movement of the lamp 7 will automatically break the circuit running to the lamp and the outward movement of said parts will automatically 25 close said circuit, whereby said lamp will be automatically extinguished and lighted respectively. The lamp circuit is made, it will be understood, by connecting one of the wires 8 and 9 with one of the 30 contacts 16, the other wire and contact connected in the usual manner to a source of electricity, which connection is not shown in the drawings, but will be understood to be accomplished in the usual manner of extending 35 said conductors 8 and 9 into the casing 10^b and connecting the proper one of the same with the contact strips 16, one to each strip.

It will be understood that changes and 40 modifications may be made without departing from the spirit of the invention.

What we claim is:

1. A lighting fixture comprising in combination, an adjustable light support, a switch 50 for opening and closing the circuit for said light, said switch having a movable member controlling the mechanism thereof and push and pull mechanical connections between said movable support and said switch 55 for actuating the latter by the movement of the former.

2. A lighting fixture comprising in combination, an adjustable light support, a switch for opening and closing the circuit for said light, said switch having a movable member controlling the mechanism thereof and push and pull mechanical connections 60 between said movable support and said switch for actuating the latter by the movement of the former, said connections comprising a

rod actuated by the support and a chain extending between the support and said movable member.

3. A lighting fixture comprising a bracket having a tubular member, a sliding member arranged for sliding movement within the tubular portion of said bracket, said sliding member being also tubular and being provided with means for supporting an electric lamp, a switch for opening and closing 75 the circuit, and means whereby the movement of said sliding member automatically controls said switch, said means consisting of a push rod on said switch and a chain connecting the slide and a movable part of 80 the switch.

4. A lighting fixture comprising a bracket provided with means whereby it may be secured to a vertical wall, said bracket having a tubular portion extending from said wall, a lamp support having tubular portion adapted to fit and slide in the tubular portion of said bracket and also having an upwardly extending tubular portion adapted to support the lamp at its upper end, a 90 switch for opening and closing the lamp circuit and means whereby said switch may be actuated by the sliding movement of the second mentioned tubular member with reference to the first mentioned tubular member. 95

5. A lighting fixture comprising a bracket provided with means whereby it may be secured to a vertical wall, said bracket having a tubular portion extending from said wall, a lamp support having a tubular portion adapted to fit and slide in the tubular portion of said bracket and also having an upwardly extending tubular portion adapted to support the lamp at its upper end, a switch for opening and closing the lamp 100 circuit and means whereby said switch may be actuated by the sliding movement of the second mentioned tubular member with reference to the first mentioned tubular member, said switch being located in a recess in said wall. 110

6. A lighting fixture comprising a bracket provided with means whereby it may be secured to a vertical wall, said bracket having a tubular portion extending from said wall, a lamp support having a tubular portion adapted to fit and slide in the tubular portion of said bracket and also having an upwardly extending tubular portion adapted to support the lamp at its upper end, a 115 switch for opening and closing the lamp circuit and means whereby said switch may be actuated by the sliding movement of the second mentioned tubular member with reference to the first mentioned tubular member, 120 said switch being located in a recess in said wall, and said means for actuating said switch comprising push and pull connections between the second mentioned tubular member and the switch. 125

7. A lighting fixture comprising a bracket provided with means whereby it may be secured to a vertical wall, said bracket having a tubular portion extending from said wall, a lamp support having a tubular portion adapted to fit and slide in the tubular portion of said bracket and also having an upwardly extending tubular portion adapted to support the lamp at its upper end, a switch for opening and closing the lamp circuit and means whereby said switch may be actuated by the sliding movement of the second mentioned tubular member with reference to the first mentioned tubular member, said switch being located in a recess in said wall, and said means for actuating said switch comprising push and pull connections between the second mentioned tubular member and the switch, said push connection comprising a rod and the pull connection comprising a chain.
8. A light fixture comprising a bracket adapted to be secured to a vertical wall and provided with a tubular portion extending from said wall, a support for an electric lamp having a tubular portion adapted to
- fit and slide within the tubular portion of said bracket and also having an upwardly extending tubular portion provided with a lamp socket at its upper end, a switch for controlling the lamp circuit, said switch being located in a recess in said wall adjacent the end of said bracket, said switch being provided with an adjustable member movable in the direction of movement of said second mentioned tubular member and arranged for controlling the circuit opening and closing mechanism of the switch, a rod secured to said movable member of the switch and adapted to be actuated by said second mentioned tubular member, a chain extended between said switch movable member and said second mentioned tubular member and flexible connectors extending from the switch through said tubular members to the lamp socket.

In witness whereof, we hereunto subscribe our names this 24th day of April, A. D. 1919.

MARQUETTE A. HEALY.
WALTER I. KIRK.
